The ornamental design for a portable storage container, as shown and disclosed.

DESCRIPTION

FIG. 1 is a perspective view of a portable storage container showing our new design;

FIG. 2 is a front elevational view thereof; the rear elevational view being a mirror image thereof;

FIG. 3 is a top plan view thereof; with lid and latch removed for clarity of illustration;

FIG. 4 is a top plan view of a lid thereof;

FIG. 5 is a front elevational view of FIG. 4; the rear elevational view being a mirror image thereof;

FIG. 6 is a bottom plan view of FIG. 4;

FIG. 7 is a left side elevational view of FIG. 4; and, FIG. 8 is a bottom plan view of FIG. 1.
